JOSEPH S. ISIDOR, OF NEWARK, NEW JERSEY.

LOCKING MECHANISM FOR BAG-FRAMES.

1,282,843.

Specification of Letters Patent. Patented Oct. 29, 1918.

Application filed March 22, 1918. Serial No. 223,897.

To all whom it may concern:

Be it known that I, JOSEPH S. ISIDOR, a citizen of the United States, residing at Newark, in the county of Essex and State of New Jersey, have invented certain new and useful Improvements in Locking Mechanism for Bag-Frames; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention has reference, generally, to improvements in bag-frames; and the present invention relates, more particularly, to a novel locking attachment for bag-frames, combining with the hinged frame-sections 20 a lock-actuated and hasp-engaging mechanism, arranged and constructed with a view of dispensing with the additional hasp-engaging bag-frame fasteners mounted upon the outside of one of the frame sections and 25 operated independently of the main hasp-engaging lock.

The present invention, therefore, has for its principal object to provide a novel and simply constructed, as well as an easily actuated and effectively operating hasp-engaging mechanism for bag-frames, combining with the hinged frame-sections, a hasp-engaging lock, and an auxiliary hasp-engaging means, in the form of slides which are actuated 30 simultaneously with the operation of the lock-mechanism, to disengage from their normal holding or locked engagement with an arrangement of auxiliary hasps, and to dispense with the employment of additional 35 bag-frame fasteners mounted upon the outside of one of the frame-sections.

Other objects of the invention not at this time more particularly enumerated will be clearly understood from the following detailed description of the present invention.

With the various objects of the present invention in view, the said invention consists, primarily, in the novel locking-attachment for bag-frames hereinafter more fully set forth; and, the invention consists, furthermore, in the novel arrangements and combinations of the several devices and parts, as well as in the details of the construction of the said parts, all of which will be more fully described in the following specification, and then finally embodied in the clauses of the

claim which are appended to and which form an essential part of the said specification.

The invention is clearly illustrated in the accompanying drawings, in which:

Figure 1 is a top view of a bag-frame, provided with a locking attachment therefor, made according to and embodying the principles of the present invention, the two bag frame-sections being represented in a partly 60 opened and unlocked relation, so as to show in connection therewith the arrangement or disposition of the several hasp-lugs; and Fig. 2 is a front face view of the frame-sections and the locking attachment in their 65 closed relation, the usual hinged end-members or portions of the frame-sections being represented as being broken away.

Fig. 3 is a longitudinal vertical section of the outer or main frame-section and the 70 locking attachment connected therewith, the manipulating lock which is employed in connection with said frame-section for actuating the said locking attachment being represented in elevation; and Fig. 4 is a 75 horizontal section of the locking attachment said section being represented as taken on line 4—4 in said Fig. 2, looking in the direction of the arrow α .

Fig. 5 is a longitudinal vertical section of 80 the outer or main frame-section and the locking attachment connected therewith, similar to the sectional view represented in said Fig. 3, illustrating the said locking attachment mounted upon the inner face of 85 the frame-section, instead of the outer face thereof as illustrated in Figs. 1, 2, 3 and 4 of the drawings.

Fig. 6 is a detail horizontal sectional representation of the one end-portion of the 90 casing or shell and one of the hasp-engaging slides disposed therein, showing in connection with the end of the said slide, a different form of spring from that illustrated in 95 Figs. 3, 4 and 5 of the drawings.

Similar characters of reference are employed in all of the said above described views, to indicate corresponding parts.

Referring now to the several figures of the drawings, it will be seen, that the locking 105 attachment is shown in connection with that class of bag-frames known in the trade as "English" or sewed-in bag-frames, and while in the following specification I have also described the said attachment mounted upon 110 and used with the frame-sections of this type of bag-frames, it will be understood,

however, that the locking attachment may be attached to and used also with other styles and types of bag-frames.

In the present drawings, the reference-
5 characters 1 and 2 indicate the outer mem-
bers of the respective frame-sections, the
frame-section 1 having secured thereto, by
means of the usual brackets 3, or other suit-
able securing means, the usual form of verti-
10 cally disposed side-member or element 4.
In like manner, the frame-section 2 has se-
cured thereto, by means of the usual brackets
5, or other suitable securing means, the usual
form of vertically disposed side-member 6,
15 the respective leg-members of said side-ele-
ments 4 and 6 being operatively connected
by means of any usual and well-known
hinges, which, however, are not here shown.

Suitably secured to the said side-member
20 or element 6, at desired points, and project-
ing laterally from the inner faces of said
side-element 6 are a plurality of hasp-lugs,
as 7, 8, 9 and 10, each hasp-lug being pro-
vided with retaining or holding hooks 11
25 with beveled ends 12, substantially as illus-
trated in Fig. 1 of the drawings, and for
the purpose to be presently more fully de-
scribed. Suitably secured upon the inner
30 face of the side-member or element 4, by
means of rivets 13, or other suitable fasten-
ing means, is a lock-casing, as 14, containing
any suitably constructed and key-operated
lock-mechanism.

Connected with the said lock-mechanism
35 and extending in an upward direction there-
from, through an opening in the top-plate
15 of said lock-casing or shell 14 is a verti-
cally movable key-receiving member or ele-
ment, as 16, provided with wings 17 which
40 extend on opposite sides of said member or
element 16, longitudinally with relation to
the frame-section 1. In its front face, the
said lock-casing or shell 14 is provided with
a pair of suitably disposed slots or openings,
45 as 18, for entrance into the said casing or
shell 14 of the end-portions of the two hasp-
lugs 7 and 8, and the engagement of the re-
taining or holding hooks 11 of said lugs 7
and 8 with a pair of spring-controlled lock-
50 posts 19 and 20 of the usual construction,
and with which the said locking mechanism
contained in said casing or shell 14 is pro-
vided, when the two frame-sections are
brought into their closed relation.

55 Normally, the winged portion of the ver-
tically movable key-receiving member or ele-
ment 16 extends into, through and above a
suitably shaped opening, as 21, with which
the said frame-section 1 is provided, the said
60 wings 17 being each formed with an in-
clined or chamfered edge, as 22, for the pur-
poses to be presently more fully described.
As shown in the several figures of the draw-
ings, there is suitably secured upon the up-
65 per and outer face of said frame-section 1,

by means of rivets 23 and 24, or other suit-
able fastening means, a longitudinally ex-
tending shell or casing, as 25, the said shell
or casing 24 being usually open-bottomed,
as shown, and being provided in its top with
70 an opening 26, see Figs. 1 and 3 of the draw-
ings, which opening 26 is disposed over the
opening 21 in the frame-section 1, and in
which the winged portion of the said key-
receiving member or element 16 is also dis-
75 posed, substantially as shown. Slidably dis-
posed upon the upper and outer face of the
frame-section 1, and within said longitudi-
nally extending shell or casing 25 are a pair
80 of flat plates or slides, as 27 and 28, the said
slides being provided with the respective
chamfered or inclined edge-portions 29 and
30, at all times forced into operative engage-
ment or contact with the inclined or cham-
85 fered edges 22 of the respective wings 17,
by an arrangement of compressible coiled
springs, as 31 and 32, located between the
end-portions 33 and 34 of the respective
plates or slides 27 and 28 and the respective
90 end-walls 35 and 36 of the shell or casing
25, as shown in Figs. 3 and 4 of the draw-
ings, or by an arrangement of flat end-
springs 37, as represented in Fig. 6 of the
drawings. To permit of the slideable ar-
95 rangement of the said plates or slides 27 and
28, the latter are provided at proper loca-
tions with an arrangement of elongated
openings or slots, as 38, through which the
previously mentioned rivets 23 extend, as
100 shown.

Suitably connected with the respective
plates or slides 27 and 28 are downwardly
extending hasp-lug engaging posts or ele-
ments 39 and 40, which project into and
105 through, and are slidably disposed corre-
spondingly placed elongated openings or
slots 41 and 42 with which the frame-section
1 is provided, and with which posts or ele-
ments 39 and 40 the retaining or holding
110 hooks 11 of the respective hasp-lugs 9 and
10 are brought into locked or holding en-
gagement when the two frame-sections 1 and
2 are brought into their closed relation.

Thus, when the locking mechanisms with-
in the lock-casing or shell 14 has not been
locked by means of a key, and the frame-
section 2 is closed within the frame-section
1, the hasp-lugs 7 and 8 will be snapped into
holding engagement with the respective
lock-posts 19 and 20 of the locking mecha-
120 nism contained in said casing or shell 14,
and the hasp-lugs 9 and 10 will be sim-
ultaneously snapped into holding engagement
with the posts or elements 39 and 40 of the
respective plates or slides 27 and 28. When
125 it is desired to bring the frame-sections 1
and 2 into their opened relation, the key-
receiving member or element 16 is suitably
depressed whereby the locking mechanism
within the lock-casing or shell is also de-
130

pressed and the vertically movable lock-posts 19 and 20 are withdrawn from their retaining or holding engagement with the hasp-lugs 7 and 8. At the same time, the 5 inclined or chamfered edges 22 of the wings 17 in their engagement with the respective inclined or chamfered edge-portions 29 and 30 of the plates or slides 27 and 28 will force the said plates or slides in opposite directions toward the respective ends of the shell 10 or casing 25, against the action of the previously mentioned springs, so that the posts or elements 39 and 40 will also be withdrawn from their holding or retaining engagement 15 with the respective hasp-lugs 9 and 10, permitting thereby the bag-frame to be opened, as will be clearly evident. As soon as the pressure is removed from the push-post or element 16, the various parts contained in 20 the lock-casing or shell 14, as well as the plates or slides 27 and 28 will again return to their normal initial positions, so that the frame-sections can be closed.

Of course it will be understood, that the 25 construction of the locking mechanism within the casing or shell 14 is such, so that when a key is inserted in the member or post 16, the mechanism within the casing or shell 14 can be locked against movement, 30 whereby the said member or post 16 is also immovably fixed, so that it can not be depressed, and the said plates or slides 27 and 28 can not be operated.

In lieu of the arrangement of the shell 35 or casing 25, and the devices contained therein, being mounted upon the outer face of the frame-section 1, the said shell or casing 25 may be secured against the inner surface of the said frame-section 1, as shown in Fig. 40 5 of the drawings. In this case, the hasp-engaging posts or elements 39 and 40 are slidably disposed in correspondingly placed elongated openings or slots 43 and 44 with which the said shell or casing 25 is provided. 45 An ornamental plate or escutcheon, as 45, provided with a hole or opening 46 in which the winged member or post 17 may extend and move, in the manner heretofore described, may also be secured upon the outer face of 50 the frame-section 1, as shown in said Fig. 5.

In all other respects the arrangements and constructions, as well as the operations, of the several devices and parts are the same as those described in connection with Figs. 55 1 to 4 inclusive, and any further description of the same is deemed unnecessary.

Since any known construction of locking mechanism within the lock-casing or shell 14 may be employed it is not deemed necessary to further illustrate and describe any particular construction of locking mechanism in connection with this case.

Of course, I am aware that some changes may be made in the general arrangements 60 and combinations of the various devices and

parts, as well as in the details of the construction of the said parts, without departing from the scope of the present invention as set forth in the foregoing specification, and as defined in the clauses of the 70 claim which are appended thereto. Hence, I do not limit my present invention to the exact arrangements and combinations of the several devices and parts as described in the foregoing specification, nor do I confine myself to the exact details of the construction of the said parts as illustrated in the accompanying drawings. 75

I claim:

1. In combination with the frame-sections 80 of a bag-frame, hasp-lugs extending from one of said frame-sections, a locking mechanism connected with the other frame-section provided with means adapted to engage with some of said hasp-lugs, a shell or casing mounted with relation to said last-mentioned frame-section, said shell or casing and said frame-section being provided with registering openings, a vertically movable push-post connected with said locking mechanism, said push-post extending into and through said registering openings, said push-post being provided with inclined engaging portions, spring-controlled slides disposed in said shell or casing actuated by engagement of said inclined engaging portions therewith when said push-post is depressed, and means connected with said slides adapted to engage with others of said hasp-lugs. 90

2. In combination with the frame-section 100 of a bag-frame, hasp-lugs extending from one of said frame-sections, a locking mechanism connected with the other frame-section provided with means adapted to engage with some of said hasp-lugs, a shell or casing 105 mounted with relation to said last-mentioned frame-section, said shell or casing and said frame-section being provided with registering openings, a vertically movable push-post connected with said locking mechanism, said push-post extending into and through said registering openings, said push-post being provided with inclined engaging portions, spring-controlled slides disposed in said shell or casing actuated by engagement of said inclined engaging portions therewith when said push-post is depressed, and hasp-engaging post extending downwardly from said slides adapted to engage others of said hasp-lugs. 110

3. In combination with the frame-sections 115 of a bag-frame, hasp-lugs extending from one of said frame-sections, a locking mechanism connected with the other frame-section provided with means adapted to engage 120 with some of said hasp-lugs, a shell or casing mounted with relation to said last-mentioned frame-section, said shell or casing and said frame-section being provided with registering openings, a vertically movable push-post 125

connected with said locking mechanism, said push-post extending into and through said registering openings, wings extending on opposite sides of said push-post, said wings being provided with inclined engaging edges, spring-controlled slides disposed in said shell or casing actuated by engagement of said inclined engaging edges therewith when said push-post is depressed, and means connected 10 with said slides adapted to engage with others of said hasp-lugs.

4. In combination with the frame-sections of a bag-frame, hasp-lugs extending from one of said frame-sections, a locking mechanism connected with the other frame-section provided with means adapted to engage with some of said hasp-lugs, a shell or casing mounted with relation to said last-mentioned frame-section, said shell or casing and said 15 frame-section being provided with register-

ing openings, a vertically movable push-post connected with said locking mechanism, said push-post extending into and through said registering openings, wings extending on opposite sides of said push-post, said wings being provided with inclined engaging edges, spring-controlled slides disposed in said shell or casing actuated by engagement of said inclined engaging edges therewith when said push-post is depressed, and hasp-engaging post extending downwardly from said slides 25 adapted to engage others of said hasp-lugs.

In testimony that I claim the invention set forth above I have hereunto set my hand this 18th day of March, 1918.

JOSEPH S. ISIDOR.
